CLAIM

The ornamental design for an orthopedic pillow as shown and described.

DESCRIPTION

FIG. 1 is a rear perspective view of an orthopedic pillow showing the new design;

FIG. 2 is a front perspective view thereof;

FIG. 3 is a top plan view thereof;

FIG. 4 is a bottom plan view thereof;

FIG. 5 is a right elevation view thereof;

FIG. 6 is a left elevation view thereof;

FIG. 7 is a rear elevation view thereof, primarily showing a surface adapted to selectively engage a user's side; and,

(Continued)

FIG. 8 is a front elevation view thereof, primarily showing a surface adapted to selectively engage a user's arm.

1 Claim, 8 Drawing Sheets
